UNITED STATES PATENT OFFICE

154,675

DESIGN FOR A COMBINED ICE-CREAM CABINET AND SODA FOUNTAIN

Richard I. Gray, Decatur, Ill.

Application July 8, 1948, Serial No. 147,434

Term of patent 14 years
(Cl. D2—3)

To all whom it may concern:

Be it known that I, Richard I. Gray, a citizen of the United States, residing at Decatur, in the county of Macon and State of Illinois, have invented a new, original, and ornamental Design for Combined Ice-Cream Cabinet and Soda Fountain, of which the following is a specification, reference being had to the accompanying drawing, forming part thereof.

The figure is a perspective view of a combined ice-cream cabinet and soda fountain, showing my new design.

The end of the cabinet and fountain not shown is plain and substantially the same as the end shown on the drawing and the back is also substantially plain.

I claim:

The ornamental design for a combined ice-cream cabinet and soda fountain, as shown and described.

RICHARD I. GRAY.
